WIRE DRAWING

John C. Garand, Springfield, Mass.

Application November 27, 1941, Serial No. 420,627

2 Claims. (Cl. 80—34)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a wire drawing die and more particularly to a die that will not tear stock of tough material, such as stainless steel which tends to stick to dies of conventional type thereby causing such tearing.

The present application constitutes a continuation in part of my co-pending U. S. application, Serial No. 241,820, filed Nov. 22, 1938.

The specific nature of the invention as well as other objects and advantages thereof will clearly appear from a description of a preferred embodiment as shown in the accompanying drawing in which:

The single figure of the drawing is a schematic elevational view of a die designed in accordance with my invention.

As shown in the drawing a pair of opposed die members 10 and 11 are mounted for rotation on spaced parallel shafts 12 and 13, respectively.

The die member 10 is formed with a cylindrical forming surface 14 and the die member 11 is formed with a centrally disposed cylindrical forming surface 15 bounded by opposed outwardly and inwardly directed symmetrically arranged beveled surfaces 16 beveled at angles more specifically referred to hereinafter.

A second pair of die members 17 and 18 have lower planar surfaces 19 and cylindrical forming surfaces 21, 22, respectively, with upper beveled edges 23 interposed between the rollers 10 and 11 in symmetrical overlapped relation. The planar surfaces 19 of die members 17 and 18 bearingly engage the beveled surfaces 16 of die member 11 in parallel relation and similarly the beveled edges 23 of these die members are bearingly engaged by the surface 14 of die member 10 in parallel relation. The die members 17 and 18 are mounted for rotation on inclined axes 24 and 25 as shown in the drawing.

The axes of shafts 24 and 25 are arranged in the same plane as the axes of shafts 12 and 13 and the die members 10 and 11 are so disposed as to make the distance *a* from the axis of shaft 12 to the cylindrical forming surface 15 of die member 11 substantially equal to the radius *b* of either die member 17 or 18.

The die opening formed by the forming surfaces 14, 15, 21 and 22 is trapezoidiform in cross section to form the stock being drawn into wire 26 of a similar section. I have found that when wire of proper trapezoidiform section is coiled

into a helical spring with the narrow edge of such section disposed on the interior of the spring being formed, that due to the compression of the metal in the proximity of this narrow edge and the tension of the metal on the outer or wide edge of the wire section the dimensions of the section will be substantially equalized resulting in a finished spring formed of wire substantially rectangular shape in cross section.

10 The angle of the bevels 16 and 20 will be such as to provide for parallel bearing engagement thereof with the surfaces 19 of die members 17 and 18 and surface 14 of die member 10, respectively, in a manner to provide a die opening that 15 will form wire 26 of a wedge shape in cross section that will result in a spring having the stock of its coils of substantially rectangular shape in cross section when coiled as above explained.

By the foregoing arrangement a die has been 20 provided wherein the linear velocities of the die members acting upon the stock being drawn are of substantially the same or only small difference whereby the action thereof upon the stock is uniform eliminating tendency to tear the stock, and 25 the die opening is maintained at substantially the same cross sectional area as the die members rotate due to the inter-bearing relation shown in the drawing.

Having now described a present preferred embodiment of the invention, I claim:

30 1. A die for drawing wire embodying a first pair of die members comprising a first die member having a cylindrical forming surface and a second die member having a cylindrical forming surface of less width than said first recited cylindrical forming surface, said second die member also being provided with beveled surfaces extending outwardly and inwardly from the cylindrical forming surface thereof in symmetrical relation, 35 a pair of parallel shafts rotatably mounting the first and second die members with their forming surfaces in spaced parallel symmetrically aligned relation, a second pair of die members each comprising cylindrical forming surfaces and planar lower surfaces arranged normally to the cylindrical forming surfaces, said second pair of die members each being formed with beveled edges extending upwardly and inwardly from the cylindrical forming surfaces thereof, a second 40 pair of shafts having their axes in the plane of the axes of said first pair of shafts rotatably mounting the second pair of die members with the planar surfaces thereof in parallel bearing relation to the beveled surfaces respectively of the second die member and the beveled surfaces 45 50 55

thereof in parallel bearing relation to the cylindrical surface of the first die member; whereby the forming surfaces of all of said die members cooperate to form a die opening of trapezoidiform in cross section.

2. A die for drawing wire embodying a first pair of die members comprising a first die member having a cylindrical forming surface and a second die member having a cylindrical forming surface of less width than said first recited cylindrical forming surface, said second die member also being provided with beveled surfaces extending outwardly and inwardly from the cylindrical forming surface thereof in symmetrical relation, a pair of parallel shafts rotatably mounting the first and second die members with their forming surfaces in spaced parallel symmetrically aligned relation with the distance from the axis of one shaft to the forming surface of the die member on the other shaft equal to a distance a , a sec- 20

5 ond pair of die members each comprising cylindrical forming surfaces a radius $b=a$ and planar lower surfaces arranged normally to the cylindrical forming surfaces, said second pair of die members each being formed with beveled edges extending upwardly and inwardly from the cylindrical forming surfaces thereof, a second pair of shafts having their axes in the plane of the axes 10 of said first pair of shafts rotatably mounting the second pair of die members with the planar surfaces thereof in parallel bearing relation to the beveled surfaces respectively of the second die member and the beveled surfaces thereof in parallel bearing relation to the cylindrical surface of the first die member; whereby the forming surfaces of all of said die members cooperate to form a die opening of trapezoidiform in cross section.

JOHN C. GARAND.
